CLAIM

I claim the ornamental design for a fingernail polish bottle, as shown and described.

DESCRIPTION

FIG. 1 is a right, front, top perspective view of a fingernail polish bottle showing our new design;

FIG. 2 is a front elevational view thereof;

FIG. 3 is a right side elevational view thereof, the left side being a mirror image;

FIG. 4 is a left, rear, bottom perspective view thereof;

FIG. 5 is a right, front, top perspective view of a second embodiment of FIG. 1;

FIG. 6 is a front elevational view of FIG. 5;

FIG. 7 is a right side elevational view of FIG. 5, the left side being a mirror image;

FIG. 8 is a left, rear, bottom perspective view of FIG. 5;

FIG. 9 is a right, front, top perspective view of a third embodiment of FIG. 1;

FIG. 10 is a front elevational view of FIG. 9;

FIG. 11 is right side elevational view of FIG. 9, the left side being a mirror image; and,

FIG. 12 is a left, rear, bottom perspective view of FIG. 9.
